US00D512737S

(12) **United States Design Patent** (10) Patent No.: **US D512,737 S**
(45) Date of Patent: **** Dec. 13, 2005**

(54) **DLP PROJECTOR**

(75) Inventors: **Sadayoshi Azuma**, Kyoto (JP);
Yoshihito Morishita, Neyagawa (JP)

(73) Assignee: **Matsushita Electric Industrial Co., Ltd.**, Osaka (JP)

(**) Term: **14 Years**

(21) Appl. No.: **29/208,720**

(22) Filed: **Jul. 2, 2004**

(30) **Foreign Application Priority Data**

Apr. 9, 2004 (JP) 2004-011039

(51) LOC (6) Cl. **16-02**

(52) U.S. Cl. **D16/230**
